FIG. 4

FIG. 5

FIG. 6

FIG. 7

FIG. 8

FIG. 1 is a front view in elevation of a medical drainage bag showing my new design;

FIG. 2 is a rear view in elevation of the bag of FIG. 1;

FIG. 3 is a rear view in perspective of the bag of FIG. 1;

FIG. 4 is a front view in perspective of the bag of FIG. 1;

FIG. 5 is a right side view of the bag of FIG. 1;

FIG. 6 is a left side view of the bag of FIG. 1 with the draw off tube removed from its protective pocket in the well panel of the bag;

FIG. 7 is a bottom plan view of the bag of FIG. 1; and

FIG. 8 is a top plan view of the bag of FIG. 1.

I claim:

The ornamental design for a medical drainage bag or similar article, substantially as shown and described.
